NOISELESS RETURN FOR TYPEWRITER CARRIAGES

Friedrich Wunderlich, Nuremberg, Germany, assignor to the firm Triumph-Werke Nürnberg A.-G., Nuremberg, Germany

Application April 4, 1938, Serial No. 200,007
In Germany May 27, 1937

7 Claims. (Cl. 197—88)

This invention relates to a noiseless return for typewriter carriages. Various attempts have already been made to solve this problem, but the suggestions hitherto made have not led to a completely satisfactory result. Thus for example it has been proposed to open out by frictional action, by means of a bell-crank lever, a divided coupling or sleeve which is provided in the joint with teeth. The disadvantage of this appliance consists in the fact that the teeth can only engage intermittently or in jerks, and that means would furthermore have to be provided for locking, which occasion a great deal of noise. According to another suggestion, locking or ratchet teeth are brought out of engagement by means of an auxiliary lever moved through the medium of a cam wheel. This appliance also does not work noiselessly. An attempt has therefore been made to disengage the ratchet tooth by means of a frictional member, which is actuated by the ratchet wheel or by the spring casing. This method of disengagement is however exceedingly unreliable, since the checking spring which is necessary therein is very liable to be damaged.

Now the object of the present invention is to provide a completely noiseless carriage return, which will ensure a reliable disengagement of the ratchet tooth, and this object is attained by effecting the disengagement of a divided ratchet tooth under the action of the weight of the ratchet tooth or of a supplementary spring, while the engagement thereof is effected through the medium of a friction member actuated by the ratchet wheel.

The invention is illustrated by way of example in the accompanying drawings, in which

Figure 1 shows the feeding or ratchet appliance during the retraction of the carriage;

Figure 2 shows the engagement of the ratchet tooth;

Figure 3 shows the feeding or ratchet appliance in the writing position of the carriage;

Figure 4 shows the feeding or ratchet appliance during the striking of a key or of the space bar;

Figure 5 shows a section through the feeding or ratchet body in the writing position, and

Figure 6 shows a section similar to Figure 5, during the actuation of the carriage release lever or of a tabulator.

In the feeding or ratchet body 1, which is rockably supported between conical points 2 and 3, is slidably mounted in a guide bush 16 a bolt 4, which carries at one end a ratchet tooth carrier 5. On this carrier a loose ratchet tooth 6 is ro-

tatably supported about a bolt 1. The travel of the loose ratchet tooth 6 is limited in one direction by a stop 8, and in the other direction by a stop 9. The latter is constructed as an adjustable eccentric. A tension spring 10 draws the ratchet tooth 6 against the eccentric 9. The stop 8 is formed by thin metal sheets 11, for the purpose of damping the noise of the impact. On the feeding or ratchet body 1 is furthermore arranged in a known manner a fixed ratchet tooth 12. The ratchet tooth carrier 5 is subject to the pressure of a spring 15, and swings between adjustable stops 13 and 14. A tension spring 19 tends to keep the ratchet body 1 in a definite position, i. e. in which the fixed ratchet tooth 12 is out of engagement with the ratchet wheel 36. The bolt 4, which is rigidly connected with the ratchet tooth carrier 5, is supported in a long guiding bush 16, so that it can be displaced at right angles to the ratchet body 1. By a spring 17, which is held owing to screw means 18, the ratchet tooth casing bears on a collar 16a of the guiding bush 16.

In the body or frame of the writing machine a bell-crank-lever 21 is rotatably supported about a bolt 20. On the lever arm 21 is located a stop 22 for the loose ratchet tooth 6. To the other lever arm 23 is pivoted at 25 an intermediate lever 25a, provided with an abutment nose 24. The free end of the intermediate lever 25a is pivotally connected at 27 with an arm 27a, which is integral or virtually integral with a friction disc 28 supported upon the pivot 37 of the ratchet wheel. The arm 27a carries an abutment nose 26. Into it is furthermore riveted a pin 29, which engages in an elongated hole 30 in a friction shell 31. Upon the latter a spring cap 33 is mounted in slots 32. Compression springs 34 and 35 ensure the rubbing of the friction shell 31, and also of the friction disc 28, on the ratchet wheel 36, which is mounted fast upon the shaft 37. Positioning rings 38 and 39 ensure the position of the friction disc 28 and of the spring cap 33.

In Figure 1 the ratchet appliance is represented during the return of the carriage. The ratchet wheel 36 moves during this operation in the direction of the arrow 41. The arm 27a is thereby carried round in the same direction of revolution by the action of the friction disc 28 and of the friction shell 31 until the stop 24 of the lever 25a bears on it. The bell-crank lever 21 is then rocked thereby about its fulcrum 20 in such a way that the stop 22 assumes the position shown in Figure 1. By the action of the spring 15, the ratchet tooth carrier 5 is then pressed against

the stop 14, and the loose ratchet tooth 6 bears by its own weight, assisted, it may be, by a supplementary spring 10, against the eccentrically constructed stop 9. The rounded tip of the ratchet tooth 6 is thus brought out of reach of the teeth of the ratchet wheel 36, so that the latter can be freely rotated in the direction of the arrow 41, thus avoiding any noise.

If the carriage tension now comes into action, 10 in the direction of the arrow 40 in Figure 2, the arm 27^a, located on the friction disc 28, is likewise rotated in the direction of the arrow 40, until its stop 26 comes against the intermediate lever 25^a. A rigid connection of the arm 27^a 15 to the bell-crank lever 21 is thereby provided. The latter is now carried along in the movement of the ratchet wheel and revolves about its axis 20, so that its stop 22 bears against the loose ratchet tooth 6, and brings the latter by 20 its movement within reach of the teeth of the ratchet wheel 36. Since the pivots 31, 21 and 25 are in one plane, and the arms 27^a and 25^a 25 are therefore in the dead centre position, the stop 22 of the bell-crank lever 21 is now immovable, without any fluctuation in the further rotation of the ratchet wheel in the same direction.

During the further rotation of the ratchet wheel 36 in the direction of the arrow 40, the 30 ratchet members then assume the position shown in Figure 3, in which the loose ratchet tooth 6 bears firmly against a tooth of the ratchet wheel 36 under the action of the carriage tension. The loose ratchet tooth 6 is 35 thereby pressed against the stop 8 on the ratchet tooth carrier 5, as a result of which the latter is carried along until the tooth 6 bears against the adjustable stop 13. In this position of the parts the carriage is in the writing position.

40 If a key is now depressed, the ratchet body 1 is oscillated in its bearings 2 and 3 in the direction of the arrow 42 in Figure 5. Owing to this rocking movement the ratchet tooth carrier 5 and the loose ratchet tooth 6 move in a 45 lateral direction out of reach of the teeth of the ratchet wheel 36, at the same time putting in the fixed ratchet tooth 12. The ratchet tooth carrier 5, under the action of the spring 15, now bears upon the stop 14, while the loose 50 ratchet tooth 6, by its own weight, or by the action of the supplementary spring 10, finds its motion limited by the stop 22. This stop has a fixed position, since, as explained above, it is prevented from deflecting by the straight 55 position of the lever arm 27^a and the intermediate link or lever 25^a. Upon further feeding the fixed ratchet tooth 12 is disengaged, and the next tooth of the ratchet wheel 36 bears against the loose ratchet tooth 6, which is then 60 rocked, together with the ratchet tooth carrier 5, until the tooth 6 has come into contact with the stop 13 and the position of the ratchet members represented in Figure 3 recurs.

During the feeding of the carriage, therefore, 65 the stop 22 remains in the position into which it has been moved by the movement of the levers 27^a and 25^a into a straight line. When the carriage is released, which occurs either upon operation of the carriage release lever, or in 70 tabulating, the bolt 4, through the medium of a ratchet or feeding member not shown, is pressed in the direction of the arrow 43 in Figure 6, the plane perpendicular to the fixed tooth remaining parallel to the plane perpendicular to 75 the loose tooth. A parallel displacement of the

ratchet tooth carrier 5 with the loose tooth 6 to the fixed tooth 12 therefore takes place. The ratchet wheel is thereby completely set free and can be rotated continuously in any direction. This method of disengaging the ratchet tooth 5 may also be employed with a different construction of the loose ratchet tooth.

The long bearing of the bolt 4 in the bush 16 enables the movable ratchet tooth to have a good seat in every case.

I claim:

1. In a writing machine comprising a frame and a carriage reciprocable on the frame, the provision of means for the noiseless return of the carriage, comprising a ratchet wheel rotatably mounted in the frame, a movably mounted ratchet tooth capable of engaging with the ratchet wheel but tending by its own weight to move out of engagement therewith, a movable abutment for moving the said ratchet tooth into engagement with the ratchet wheel, and actuating means, including friction driving means, operatively connected to the abutment and to the ratchet wheel, for moving the abutment in the direction to bring the ratchet tooth into engagement with the ratchet wheel, on the ratchet wheel being turned in the normal carriage-feed direction and moving the abutment in the opposite direction, on the ratchet wheel being turned in the reverse direction, so as to allow the ratchet tooth to pass out of engagement with the ratchet wheel under its own weight.

2. In a writing machine comprising a frame and a carriage reciprocable on the frame, the provision of means for the noiseless return of the carriage, comprising a ratchet wheel rotatably mounted in the frame, a movably mounted ratchet tooth, capable of engaging with the ratchet wheel but tending by its own weight to move out of engagement therewith, spring 40 means assisting the disengagement of the ratchet tooth from the ratchet wheel, a movable abutment for moving the said ratchet tooth into engagement with the ratchet wheel, and actuating means, including friction driving means, operatively connected to the abutment and to the ratchet wheel, for moving the abutment in the direction to bring the ratchet tooth into engagement with the ratchet wheel, on the ratchet wheel being turned in the normal carriage-feed 45 direction and moving the abutment in the opposite direction, on the ratchet wheel being turned in the reverse direction, so as to allow the ratchet tooth to pass out of engagement with the ratchet wheel under its own weight with the 50 assistance of said spring.

3. In a writing machine comprising a frame and a carriage reciprocable on the frame, the provision of means for the noiseless return of the carriage, comprising a ratchet wheel rotatably 60 mounted in the frame, a ratchet tooth carrier, a ratchet tooth pivotally mounted on the ratchet tooth carrier, the said ratchet tooth being capable of engaging with the ratchet wheel but tending by its own weight to move out of engagement therewith, a movable abutment for moving the said ratchet tooth into engagement with the ratchet wheel, and actuating means, including friction driving means, operatively 65 connected to the abutment and to the ratchet wheel, for moving the abutment in the direction to bring the ratchet tooth into engagement with the ratchet wheel, on the ratchet wheel being turned in the normal carriage-feed direction and moving the abutment in the opposite direction, 70

on the ratchet wheel being turned in the reverse direction, so as to allow the ratchet tooth to pass out of engagement with the ratchet wheel under its own weight.

4. In a writing machine comprising a frame and a carriage reciprocable on the frame, the provision of means for the noiseless return of the carriage, comprising a shaft rotatably mounted in the frame, a ratchet wheel mounted fast on the shaft, a movably mounted ratchet tooth capable of engaging with the ratchet wheel but tending by its own weight to move out of engagement therewith, a friction member mounted loose on the shaft, an arm rigid with the friction member, a bell crank lever pivotally mounted on the machine frame, an intermediate link connecting the bell crank lever to the arm of the friction member, a movable abutment adjustably secured to the bell crank lever and capable of moving the movable ratchet tooth into engagement with the ratchet wheel, a stop on the intermediate link for limiting its movement, a friction shell surrounding the friction member, and springs urging the friction shell into frictional engagement with the ratchet wheel.

5. In a writing machine comprising a frame and a carriage reciprocable on the frame, the provision of means for the noiseless return of the carriage, comprising a shaft rotatably mounted in the frame, a ratchet wheel mounted fast on the shaft, a movably mounted ratchet tooth capable of engaging with the ratchet wheel, but tending by its own weight to move out of engagement therewith, a friction member mounted loose on the shaft, an arm rigid with the friction member, a bell crank lever pivotally mounted on the machine frame, an intermediate link pivoted at one end to the arm of the friction member and at the other end to one arm of the bell crank lever, a movable abutment adjustably secured to the other arm of the bell crank lever and capable of moving the movable ratchet tooth into engagement with the ratchet wheel, means for producing frictional engagement between the friction member and the ratchet wheel, a stop on the arm of the friction member, this stop bearing against the intermediate link when the movable ratchet tooth comes into engagement with the ratchet wheel and when the pivotal axis of the connection between

the intermediate link and the arm of the friction member is in the plane containing the axis of the ratchet wheel shaft and the pivotal axis of the connection between the intermediate link and the bell crank lever.

6. In a writing machine comprising a frame and a carriage reciprocable on the frame, the provision of means for the noiseless return of the carriage, comprising a feeding body rockably mounted on the writing machine frame, a bearing bush secured to the feeding body, a pivot slideable in the bearing bush, a ratchet wheel rotatably mounted in the writing machine frame, a ratchet tooth carrier oscillatably mounted on the said slideable pivot, a ratchet tooth pivotally mounted on the ratchet tooth carrier, the said ratchet tooth being capable of engaging with the ratchet wheel but tending by its own weight to move out of engagement therewith, a movable abutment capable of moving the said ratchet tooth into engagement with the ratchet wheel, and a friction member for actuating the said movable abutment.

7. In a writing machine comprising a frame and a carriage reciprocable on the frame, the provision of means for the noiseless return of the carriage, comprising a feeding body rockably mounted on the writing machine frame, a bearing bush secured to the feeding body, a pivot slideable in the bearing bush, a ratchet wheel rotatably mounted in the writing machine frame, a ratchet tooth carrier oscillatably mounted on the said slideable pivot, a ratchet tooth pivotally mounted on the ratchet tooth carrier, the said ratchet tooth being capable of engaging with the ratchet wheel but tending by its own weight to move out of engagement therewith, a friction member mounted loose on the shaft, an arm rigid with the friction member, a bell crank lever pivotally mounted on the machine frame, an intermediate link connecting the bell crank lever to the arm of the friction member, a movable abutment adjustably secured to the bell crank lever and capable of moving the movable ratchet tooth into engagement with the ratchet wheel, a friction shell surrounding the friction member, and springs urging the friction shell into frictional engagement with the ratchet wheel.

FRIEDRICH WUNDERLICH. 50
